UNITED STATES PATENT OFFICE.

THOMAS H. THORNE, OF VANCOUVER, BRITISH COLUMBIA, CANADA.

CIGARETTE-BOX.

985,859.

Specification of Letters Patent. Patented Mar. 7, 1911.

Application filed June 3, 1909. Serial No. 499,963.

To all whom it may concern:

Be it known that I, THOMAS H. THORNE, a subject of the Kingdom of Great Britain, residing at Vancouver, in the county of 5 Vancouver and Province of British Columbia, Canada, have invented certain new and useful Improvements in Cigarette-Boxes, of which the following is a specification.

This invention relates to boxes for holding 10 and serving or detaching cigarettes, or other small elongated articles, one at a time for ready removal.

The principal object of my invention is to provide an effective device, in a cigarette 15 box which, by hand or finger manipulation may be readily operated for lifting or ejecting cigarettes, one or more at a time for removal, without danger of chafing or breaking the wrapper, or spilling the contents of 20 the box.

Another object is to provide a well closed box in which cigarettes may be safely packed for the trade, without the use of foil, or silver paper, or other packing material for 25 protecting them.

The matter constituting my invention will be defined in the claims.

I will now describe the details of construction of my improved box by reference to the 30 accompanying drawing, in which—

Figure 1 represents a perspective view of a cigarette box embodying my invention. Fig. 2 represents a longitudinal vertical section thereof. Fig. 3 represents an end view. 35 Fig. 4 represents a transverse section. Fig. 5 represents a section of a modification.

The cigarette box 2 is made of card-board or heavy paper and is of the kind used in the trade, though my invention may be applied to a special box for pocket use and may be made of any desired material. One end of the box is provided with a longitudinal slot 3 adapted for a sliding stud or button, and at the top edge with a short opening 40 4 for permitting the passage of a single cigarette. In the lower end of the box is fitted a filling or shoulder strip 5 for supporting the lower ends of the cigarette on the same level as the foot piece 12 of the 45 lifting device. The cigarette lifter or ejector 6 is constructed of a longitudinal sliding stem 7, which may be of card-board, and provided with a hinged portion 8, to the upper end of which is secured a cover 10 50 having side stays 11. The cover 10 is of the proper size to neatly close the top open-

ing 4. The card-board stem 7 is transversely scored or creased to form a hinge 9. The lower end of the sliding stem 7 is made with a foot piece 12 adapted for supporting the 60 lower end of a single cigarette. To about the middle portion of the stem 7 is secured a stud or button 13 by means of a short shank adapted to pass through slot 3. This stud may be of paper and the inner ends 65 may be simply pasted to the inner face of stem 7 as indicated in Fig. 4. A retracting cord 14 is secured by a knot 15 or other means to the end of the box near the top thereof, as shown in Fig. 3, and near the 70 lower end of the hinged portion 8 as indicated in Figs. 1 and 2.

The box is filled with cigarettes α in any desired manner before closure of the box, or the cigarettes may be inserted through 75 the opening 4 until the box is filled. The box being filled with cigarettes and the lifting or ejecting device 6 being down, thereby closing the opening 4 by the cover 10, the ejector may be readily raised by the finger 80 pressing upward on stud 13. As the ejector is raised to its upper limit the retracting cord 14 draws back the hinged portion 8, as shown in the drawing, freely exposing 85 the upper end of a cigarette, which may be readily removed without breaking or crumpling the end. The box being packed and the cover 10 closed down, the latter may be 90 covered with a revenue stamp or other small label pasted over it so that the box may be completely sealed. With this construction 95 and arrangement I may entirely dispense with tin foil or silver paper or any other kind of packing material. After one cigarette has been removed the box may be turned with the end containing the ejector 100 downward so that the next cigarette will rest upon the ejector with its lower end on the foot piece 12 so that it may be lifted and removed as above described.

It will be evident that the box with my lifting or ejecting device is very convenient for serving cigarettes and has a number of advantages in practical use.

While I have shown and described my 105 box as adapted for cigarettes, I wish it understood that it may be used for dispensing other elongated articles, cylindrical or otherwise, such as cigars, matches, etc. The details of construction may also be modified 110 without departing from the spirit and scope of my invention.

Having described my invention, what I claim, and desire to secure by Letters Patent, is—

1. The combination with a casing having a top opening for passage of a cigarette and a longitudinal slot in the adjacent end, of a sliding ejector having a stud in the slot, a foot piece for a cigarette, and an upper hinged portion provided with a cover for said top opening, whereby a single cigarette may be raised from the box and its upper end freely exposed for removal without breaking, substantially as described.

2. A cigarette box comprising a casing having a top opening, for permitting the passage of one cigarette at a time, and a longitudinal slot in the adjacent end, in

combination with a sliding ejector device composed of a stem having a foot piece for one cigarette, a hinged upper portion provided with a cover for closing said top opening and a stud working in said slot, and a retracting cord connecting with the wall of the box and with said hinged portion of the stem for drawing it back, whereby a cigarette may be raised and the upper end freely exposed, substantially as described.

In testimony whereof I affix my signature in presence of two witnesses.

THOMAS H. THORNE.
